JOURNAL BOX LID

George R. Andersen, Oak Park, Ill.

Application August 24, 1945, Serial No. 612,408

3 Claims. (Cl. 308—44)

1

This invention relates to enclosure covers and has special reference to a lid for a standard rail-road car journal box.

The standard journal box now in use is adapted to be associated with an axle and provides a source of lubricant for the axle and its associated bearings. In ordinary practice the entire journal box is an integral casting and is provided with the usual opening through which the axle and bearings are serviced. The opening is normally adapted to be closed by the lid, and, since the journal box is a casting, the edges of the opening are usually rough, resulting in difficulty in affecting a tight fit of the lid upon the periphery of the opening so that dirt, grit, snow, rain, etc., may enter the box if provision is not made to prevent it.

Consequently it is the principal object of this invention to provide a journal box lid so constructed as to provide adequate protection against entry of foreign matter into the journal box.

Another object of the invention is the provision of a journal box lid which is inexpensive to make and maintain and which fulfills all requirements expected of it in service.

Another object of the invention is the provision of a journal box lid having flanges overlapping corresponding sides of the journal box and formed so as to almost engage said sides remote from the service opening to said box and thereby to materially retard passage of air between the sides of the box opening and coperating areas of the lid and consequently reduce entry of foreign matter into the box.

Present journal box lids are usually pressed of flat material and are not provided with side flanges, other than a slightly turned edge for stiffening purposes. As a consequence of this, due to the high speed of trains, the pressure of the air currents against the windward side of the box is sufficient, together with the vibration of the lid due to service movements of the car, to jar the box lid sufficiently for undesired entry of foreign matter blown into the box by said currents. It is, therefore, one of the more specific objects of the invention to provide a flanged or hood type of journal box lid which will reduce to a bare minimum the amount of foreign matter entering the box through the service opening thereof.

Journal box lids are usually hinged at the top to the journal box and in service are required to be opened several times a day, and experience shows that the face of the box opening wears unevenly or irregularly and that the lugs wear irregularly, resulting in positive openings between

2

lid and box for direct entry of foreign matter therethrough, and causing added labor, expense and material to service said boxes. With my improved flanged or hood type of lid, in actual use on a large midwestern railroad, the labor cost in servicing journal boxes has been reduced fifty percent, the average quantity of foreign matter entering the box has been reduced to materially under fifty percent, and consequently the liability of hot-boxes has been reduced to a minimum.

Other objects and advantages of the invention will appear in the following description thereof.

Referring now to the accompanying drawing wherein like reference characters indicate like parts.

Figure 1 is a front elevation of a journal box lid incorporating my invention.

Figure 2 is a cross section through the lid on line 2—2 of Figure 1 and the associated part of the journal box.

Figure 3 is a cross section on line 3—3 of Figure 1 taken at right angles to Figure 2.

In the drawings a portion of the journal box is shown at 1 and is provided with the usual opening 2 and the upper hinge lug 3 disposed adjacent the opening and cast integral with the journal box. This lug 3 is provided with a hole 4 adapted to receive a pivot pin for pivotally mounting the journal box lid 5 on the journal box through the spaced hinge butts 6.

The lid comprises a main paneled body portion 7 or plate having its bottom 8 and sides 9 inwardly flanged. The upper edge is interrupted and formed with the spaced hinge butts 6 which are preferably continuations of the material of which the body portion is formed and bent into hollow cylindrical form adapted to surround the pivot pin to provide the pivotal connection therefor. The outer edges of each butt 6 is formed with a projection 10 which may be bent downwardly across the ends of the pin to thereby maintain it in place.

It will be noted in Figure 2 that the contour of the bottom wall of the journal box adjacent the opening 2 is of somewhat ogee form, as at 11, and that the body portion 7 of the lid extends across and contacts, as at 12, the bottom edge of the opening.

The Association of American Railroads, Operations and Mechanical Division Specification M-120-45 provides:

“(b) The sides of the lid, and the top portion outside of the hinge lugs, shall have a $\frac{1}{4}$ in. flange, . . .”

The flange 8 not only extends inwardly so as

to overlap the ogee portion 11 of the bottom wall and the side walls of the journal box at least three times the minimum required by the Association of American Railroads rules until it almost contacts the outer surface of said ogee portion 11 of bottom wall, leaving a slight opening 13, but is also so formed that it cooperates with the included portion of said ogee wall to form an enlarged space 20 having a cross section larger than the cross section of the slight opening 13 so that the force or pressure of any air currents passing through the slight opening 13 would be materially reduced by expanding or circulating into the enlarged opening 20, thus reducing the force thereof to pass between the lid and the portion 7 of the journal box. This latter opening 20 thus would form a trap for foreign matter entering therein with said air currents.

In Figure 3 it will also be noted that the side walls 10 of the journal box are substantially parallel and that the inwardly extending side flanges 9-9 are in close proximity to the exterior surfaces of said sides 16, as at 17, to form a shield to materially retard passage of air between the sides of the box opening and cooperating areas of the lid.

The flanges 8 and 9-9 preferably extend continuously about the sides and bottom of the lid.

It will be noted in Figures 2 and 3 that the flanges 8 and 9-9 are continuously of a depth at least three times beyond that which would be necessary for a mere stiffening flange for the lid in order to comply with the Association of American Railroads rules.

The unusual depth and taper of these flanges because the lid to adjust itself in relation to the walls of the box and to the service opening therein. See Figure 3.

Projecting downwardly and outwardly from the bottom portion of the flange 8 is provided a lip or preflange 23 which lip is provided with an aperture or hole 24, and a notch 25 directly therebelow and in alignment therewith, which notch prevents a packing iron and hook 26 from slipping sideways when said hook is in engagement with the aperture 24, as indicated in dotted lines, Figure 2.

My invention has to do with the journal box lid and its relation to the box as above described, and, of course, it is provided with the usual spring secured thereto and to the respective sides of the hinge lug for respectively urging and maintaining the lid in closed and open positions. All journal box lids are dependent upon spring pressure to maintain contact of the lid with the periphery of the box opening. In the fall of 1945 the Association of American Railroads Committee on Lubrication of Cars and Locomotives conducted lengthy field observations as to the fit of lids on journal boxes of railroad freight cars and of 2671 boxes examined only 96 met A. A. R. requirements and 1935 required 10 pounds or less pull to open. It is thus practically obvious that with the increased speed of freight trains, rough road beds, buffing shocks, vibration, etc., that these lids, even though equipped with springs to hold them closed, bounce open more than the width of the $\frac{1}{4}$ " flange and thus the box is open for the direct entrance of foreign matter, which is the

primary cause of hot boxes. The spring is covered with the usual spring housing. Neither the spring nor spring housing are shown in the drawings since they are common and well known in the art, but, of course, would have to be assembled with the lid to make it properly function on the journal box.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

15 I claim:

1. A rectangular lid for closing the service opening of a railway car journal box, said lid comprising a body portion adapted for pivotal connection along one of its sides to said box and engageable with the edges of said opening to form a seal for said opening, said lid having a continuous flange about the other three sides thereof adapted to overlap the corresponding walls of said opening at least three times the required width of a stiffening flange and to almost engage the exterior of said box remote from said edges and to provide an enlarged space adjacent the edge opposite said pivotal connection when the lid is in closed position to reduce the wind pressure against the lid at its place of engagement with said last mentioned edge.

2. A lid for closing the service opening of a railway car journal box, said lid comprising a body portion adapted for pivotal connection along one of its sides to said box and engageable with the edges of said opening, said lid having a flange extending continuously around the other three sides thereof and adapted to overlap the corresponding walls of said opening at least three times the required width of a stiffening flange and in slightly spaced relation thereto when the lid is in closed position.

3. A rectangular lid for closing the service opening of a railway car journal box, said lid being adapted for pivotal connection along one of its sides to one wall of said box and having a continuous flange about the other three sides thereof formed to overlap the corresponding walls of said opening at least three times the required width of a stiffening flange when in closed position and to almost engage said walls remote from said opening and also to provide an enlarged space between the place where the lid overlaps the wall opposite said pivotal connection and the place where the lid almost engages said last mentioned wall.
